PROCESS OF PRODUCING THICK BUTT SHINGLES AND SUCH SHINGLES

Benjamin Sweedler, Larchmont, N. Y., assignor,
by mesne assignments, to The Patent and
Licensing Corporation, New York, N. Y., a cor-
poration of Massachusetts

Application October 11, 1935, Serial No. 44,495

1 Claim. (Cl. 91—70)

This invention relates to shingle elements and more particularly to the manufacture of thick butt strip shingles having tabs disposed along one longitudinal edge thereof, the edges of the shingles being sealed by suitable waterproofing material. The term "shingle" is used herein in a broad sense and is intended to include elements employed for roofing, siding and other analogous construction purposes.

10 Sealed edge thick butt shingle elements have heretofore been made by hand-dipping a granular surfaced coated felt base into a bath of molten asphalt or other bituminous material, the elements allowed to drain and then surfaced with granular material. Such hand-dipping operations are expensive, since they involve time-consuming hand labor and waste of asphalt.

In Patents Nos. 1,842,448 of January 26, 1932, and 1,927,824 of September 26, 1933, there is disclosed a continuous process of making thick butt shingles with sealed edges. The invention herein is in the nature of an improvement on the continuous process disclosed in these patents.

It is an object of this invention to provide a process of making sealed edge thick butt shingles which process can be carried out in existing roofing machines with little modification thereof, and which process involves no manual manipulative step such as the dipping treatment of the prior practice. Another object is to provide a process of making thick butt shingles which results in a novel product of enhanced architectural value. This invention comprehends both the process of making the shingle and the resultant shingle product.

In accordance with this invention, one or more stripes of coating material, certain of which may be of a width sufficient to coat the tab portions of two elements cut tab-to-tab from the web, are applied to a web of roofing material. The number of stripes applied depends upon the width of the starting roofing web and the number of shingles it is desired to cut therefrom. For example, if a web of a width sufficient to produce four shingle elements cut longitudinally from the width thereof is employed, two stripes each of a width sufficient to coat the tab portions of two elements may be applied to the web. If a web of a width sufficient to produce an odd number of shingles cut longitudinally from the width thereof is employed, one of the stripes may be of a width such as to cover the tab portions of only one element and the other stripes may be of a width to coat the tab portions of two

elements cut tab-to-tab. After the coating stripes are applied they may be surfaced with mineral grit such as crushed stone, talc, mica or other of the surfacing materials employed in the roofing art. If desired, before or after the application of stripes, coating material may be applied to one or both sides of the web and surfaced with mineral grit.

The thus coated and surfaced web may then be cut longitudinally substantially midway along the aforementioned stripes of coating material each of a width sufficient to coat the tab portions of two elements to produce strips each having a relatively thick and thin portion and having tab-defining cutouts formed in the thick portion. Coating material such as asphalt or other bituminous material may then be applied to each strip covering either the side containing the aforementioned stripe or the opposite side and extending over the entire area of said side and also over the cut edges, sealing the same. Before the application of the last mentioned coating material, the cut strips may be separated to expose the cut edges, so that coating material may be readily applied thereto. The coating material thus applied may be surfaced with granular material and the strips cut transversely into shingle elements.

By applying coating material to each cut strip after the tab-thickening stripes have been applied to the web and the web cut into strips each having tabs separated by tab-defining cutouts along one longitudinal edge thereof, it is possible in one and the same operation to apply coating material to one side, preferably the exposed side, and to all cut edges, including both longitudinal edges, thereby effectively protecting the elements against weather influences.

In the accompanying drawing Fig. 1 is a diagrammatic side elevation, partially in section, of an arrangement of apparatus which may be employed for carrying out the process of this invention; Fig. 2 is a diagrammatic plan view of the web as it travels through the apparatus of Fig. 1; Fig. 3 is a diagrammatic perspective view showing the cut web as it leaves the longitudinal cutters and indicating the path of movement of the cut strips resulting in the separation thereof; Fig. 4 is a vertical section partly in elevation of apparatus which may be employed for the application of the butt thickening coating to the strips; Fig. 5 is a plan view of the apparatus of Fig. 4; Fig. 6 is a vertical section taken through one of the tabs of a thick butt shingle resulting from the practice of the process diagrammatical-

ly illustrated in Fig. 1; Fig. 7 is a vertical section taken through one of the tabs of a modified form of thick butt shingle which may result from the practice of the process of this invention, and Fig. 8 is a vertical section taken through one of the tabs of still another modified form of shingle embodying this invention.

Referring to the drawing, a web A of roofing material such as felt of the desired width is led 10 through the saturating tank 5, where it may be impregnated with a suitable waterproofing compound such as asphalt or tar. The saturated web then passes between the squeeze rolls 6 which remove excess saturant or, if desired, between 15 rolls which do not remove saturant instead of through the squeeze rolls 6, to and through drying rack 1, which allows the saturated web to cool somewhat. The web is then fed through the coating rolls 8 and 9 by means of which a relatively thin coat of weatherproofing compound such as tar or asphalt (usually of a higher melting point than that of the saturant) is applied to both faces of the impregnated sheet. Coating material may be applied to the sheet just before 20 it passes between rolls 8 and 9 by means of a spout 10, the roll 8 functioning to uniformly distribute the coating material over the face of the web. While the coating material on the web is still soft and tacky, the web passes under the 25 hoppers 11 and 12 and about reversing rolls 13 and 14.

The hoppers 11 and 12 may be of usual design, hopper 11 containing crushed slate or other wear-resisting granular material of any suitable color 30 or mixture of colors, which may be showered upon the face of the coated web by means of a distributor roll 11' to surface the web. Hopper 12 may contain talc, mica or other antistick material in finely divided form. Distributor roll 40 12' in hopper 12 showers the antistick material therein onto the rear surface of the web as it passes about roll 13, thus rendering the rear surface of the web non-cementitious.

The thus coated and surfaced web now passes 45 over guide-roll 15, cooling and calendering rolls 16 and 17, guide-roll 18 and over the plate 19 of coating appliance 19. Coating appliance 19 in the embodiment of the invention shown in Figs. 1, 4 and 5 involves two containers 21 for 50 coating material such as asphalt or other waterproofing material, each in communication with a coating roll 22 having selected portions 23 thereof, adapted to receive coating material from container 21 and apply the same in stripes to the 55 surfaced web while the latter is maintained in contact with the portions 23 of roll 22 by plate 19'. The amount of coating material delivered by portions 23 may be controlled by doctor blade 24 so that any desired thickness of coating layer 60 is applied to the surfaced web. In the embodiment of the invention shown in the drawing, two coating strips 25 and 26 are formed on the surfaced web, of a width sufficient to produce four shingles cut lengthwise therefrom, each stripe being of a width sufficient to cover 65 the tab portions of two elements cut tab-to-tab as indicated in the diagrammatic plan of Fig. 2, but it will be understood that if a wider or narrower web is employed more or less stripes respectively would be applied.

The thus coated web then passes under the hopper 27 containing mineral grit such as mica, crushed slate, etc., which is showered from the hopper onto the stripes of coating material by 70 means of a distributing roll 27'. The hopper 75

may be provided with partitions forming compartments of a width corresponding to that of the stripes 25, 26. Mineral grit in these compartments is supplied only to the stripes 25, 26 and not to the remainder of the web. In the 5 passage of the web about the reversing roll 28 the mineral grit is partially imbedded in the stripes of coating material and caused to adhere thereto.

From reversing roll 28 the web passes over 10 guide rolls 29 and 30, between rolls 31 and 32 to the cutting cylinders 33. The cutting cylinders 33 slit the web longitudinally midway along the coating stripes 25 and 26, as indicated by the reference numerals 34 and 35 and also longitudinally along line 36 which occurs on the longitudinal median line of the web. Tab-defining cutouts 37 are formed by the cutting cylinders 33 along one longitudinal edge of each of the strips 38, 39, 40 and 41 formed by the longitudinal severance of the web by means of the longitudinal cuts 34, 35 and 36. These tab-defining cutouts, it will be noted, occur in the coating stripes 25 and 26.

The cut web now passes onto conveyor bands 25 42 and 43. Strips 38 and 40 are carried by bands 42 in a downward direction while strips 39 and 41 are carried by bands 43 in an upward direction, as appears clearly from Fig. 3. Strips 38 and 40 are thus moved in the same longitudinal 30 direction as the direction of movement of the portions of the web from which they are cut but in a different horizontal plane from that in which strips 39 and 41 are moved. Strips 39 and 41 also travel in the same longitudinal direction as 35 the direction of movement of the portions of web A from which they are cut and pass over idler roll 44 while strips 38 and 40 pass over idler roll 45. Thus the strips are separated without distortion to give ready access to the cut edges, 40 permitting effective sealing of the cut edges.

The strips are now ready to have applied thereto the coating of weather-resisting material such as asphalt, tar or other bituminous material covering the entire face thereof, and which coating 45 is preferably extended to seal the cut edges including both longitudinal edges and the edges of the tab-defining cutouts. This coating material may be applied by means of any suitable coating mechanism, there being one such coating 50 mechanism for each strip. The coating mechanism may comprise a container 46 which supplies the coating material to the coating roll 47 and which may have a doctor blade such as that shown in Fig. 4 for controlling the amount of 55 coating material delivered by the coating roll 47. This coating roll is designed to supply a slight excess of coating material to the strip, the excess of coating material flowing over the longitudinal edges onto the cut edges. Instead 60 of the coating apparatus of Fig. 4, coating material may be sprayed onto the face and the edges of each strip.

While the last mentioned coating material is still soft and plastic, the strips pass under crushed 65 slate hoppers 48, one for each strip. These hoppers are equipped with distributor rolls 48' for showering crushed slate or other wear-resisting material upon the coating layer covering the strip. The strips then pass over the reversing 70 rolls 49 and 50 which press the crushed slate or other mineral grit into the plastic coating. From reversing rolls 50 the strips are conducted over the cooling rolls 51 between the feed rolls 52 over the timing rolls 53 and between the feed 75

rolls 54. Projections upon the periphery of timing rolls 53 engage in the notches between the tabs upon the strips. Transverse cutters 55 are so synchronized with the timing rolls 53 that the strips are cut along a line of severance between the tabs to form a finished thick butt shingle strip or element, as indicated in Fig. 2. From the transverse cutting mechanism 55 the strips may be fed through a chute or slide 55' 10 to a suitable packing mechanism (not shown).

Fig. 6 discloses the element resulting from the process hereinabove described. From this figure it will be noted that the element involves a felted fibrous foundation 56 which may be and 15 preferably is the usual roofing felt. This felt, as hereinabove described, is saturated with bituminous material and then both sides are completely coated with bituminous material forming coating layers 57 and 58. Mica, talc, or other 20 antistick material, layer 59, is partially imbedded in the coating layer 57 and mineral grit layer 60, such as crushed slate, is partially imbedded in the coating layer 58. A further coating 61 is supplied to the back of the element covering 25 only that portion of the back corresponding approximately to the area of the element intended to be exposed. In the case of a shingle intended to be laid with the thick butt portions inlapping relation, the coating on the back may cover 30 that portion of the area intended to be exposed plus the lap between the thick butt portions of contiguous courses. In the case of a siding element layer 61 may cover an area somewhat less than the area intended to be exposed to the 35 weather. Mineral grit layer 62 is partially imbedded in the coating layer 61. A further coating layer 63 extends over the surfacing layer 60 and covers the entire face of the element and is extended to seal both longitudinal edges 64 and 40 65 as well as all edges of the cutouts. Mineral grit layer 66 is partially imbedded in the coating layer 63.

The element of Fig. 7 differs from that of Fig. 6 chiefly in the omission of the coating layer 57 and the grit layer 59. This element, as will be understood, can readily be made by passing a roofing web through the roofing instrumentalities hereinabove described, omitting coating roll 9 which applies the coating material to the back of the web and also the surfacing hopper 12 from which surfacing material is applied to the coating layer produced by coating roll 9.

The thick butt shingle of Fig. 8 differs from that of Fig. 6 chiefly in that it has coating layer 61 and surfacing layer 62 on the face instead of on the back and has the coating layer 63 extending over the surfacing layer 62 as well as the remainder of the face of the element. The shingle of Fig. 8 may be made employing the roofing instrumentalities of Fig. 1 modified so that instead of applying a coating layer directly to the saturated web extending over the entire face thereof, the coating stripes 25 and 26 are applied directly to the face of the saturated felt web, 65 while the back of the web is coated throughout the entire extent thereof. In other words, the apparatus of Fig. 1 is modified so that instead of the coating roll 8, the coating delivery spout 10 and surfacing hopper 11, coating apparatus 19 and surfacing hopper 26 are employed. Hence, 70 when the saturated web passes through the first coating step, the back thereof will be completely covered and stripes of coating material corresponding to 25 and 26 will be applied to the face of the web. As the thus coated web passes

through the surfacing equipment the coating material is surfaced with mineral grit and the surfaced web is then passed through the cutting cylinders 33 and the other roofing instrumentalities following the cutters 33 shown on Fig. 1. 5

By the term "mineral grit" as used in the claims herein, it is intended to include surfacing materials such as mica, talc, soapstone, crushed rock, slate and other granules employed to cover the back or face of roofing. 10

It will be noted that the thick butt shingles of this invention may be made in a continuous operation employing existing roofing equipment and requires substantially no manual labor in the carrying out of any of the steps thereof. Moreover, it will be noted that the process of this invention involves the manipulation, first, of a wide web through coating and surfacing appliances, then of narrower webs produced by the cutting of the wide web into strips, which wide 20 and narrow webs are inherently of such character that they require little or no support. That is to say, the final step in applicant's process is the transverse cutting of the strips into shingles; prior to this step the base from which the elements are produced is in web form so that the inherent strength thereof may be utilized to effect its conveyance through the roofing instrumentalities, and manual manipulation or use of conveyors for handling short strips is not necessary. 25 Although the process has been described as being applicable to the production of thick butt shingles continuously from the raw felt, it is obvious that the process may be employed to make thick butt shingles from felt which has previously been saturated or from felt which has been saturated, coated and surfaced. 30

It is to be understood that this invention is not restricted to the present disclosure otherwise than as defined by the appended claims. For example, 40 instead of having the tab-defining cutouts extend to a point short of the edges of the coating stripes 25, 26 as shown in Fig. 2, these cutouts may extend beyond the edges of the coating stripes and serve as aligning guides to indicate the desired 45 position of overlying elements. Siding elements are preferably made with the cutouts extending slightly above the tab thickening stripes of coating material.

I claim:

The process of making thick butt shingles each having tabs along one longitudinal edge thereof separated by tab-defining cutouts, which comprises coating the back of a saturated felt web of a width sufficient to produce a plurality of shingles cut lengthwise therefrom with waterproofing material, applying a stripe of heat liquefied bituminous waterproofing material to the upper face only of said web, said stripe being of a width sufficient to cover the tab portions of two elements cut from the web tab-to-tab and insufficient to cover the entire area of said web, surfacing the said stripe of coating material with mineral grit, cutting the web longitudinally into strips each having tab-defining cutouts along one 60 longitudinal edge thereof, occurring in the said striped coated portion thereof, separating the cut strips, applying heat liquefied bituminous coating material to each strip overlying said coating stripe and covering the entire face thereof and the cut 65 edges, surfacing the last mentioned coating material with mineral grit and cutting each strip transversely into shingle elements. 70
